UNIDIRECTIONAL VOLTAGE GENERATOR

John A. Buckbee, Fort Wayne, Ind., assignor to
Farnsworth Television and Radio Corporation,
a corporation of Delaware

Application June 16, 1944, Serial No. 540,567

9 Claims. (Cl. 171—97)

1

This invention relates to power supply apparatus and particularly to apparatus of this character wherein the supply voltage is divided among a plurality of loads.

In the operation of multistage electron multipliers it is the conventional practice to derive the accelerating voltages for the secondary electron emissive multiplier electrodes from a voltage divider which is connected across a source of direct current energy. The voltage which is developed in each divider component is dependent upon the total current flow in that component. The total current flow consists of the circulating current through the divider component from the energy source and the electron current flow between the associated multiplier electrodes. Where it is desired that the multiplier have a substantially linear response, it is necessary that the inter-electrode accelerating voltages be maintained at substantially constant values. In order to effect this result the circulating current through the respective voltage divider components must be considerably greater than the associated inter-electrode electron current. In this manner fluctuations of the electron current due to signal variations have little or no effect upon the voltage drop in the respective divider components. In order to achieve this end with a voltage divider consisting of equal impedance components, the components must have relatively low values of impedance.

However, as is well known in the art, a voltage divider made up entirely of relatively low impedance components consumes considerable power from the source of energy. Inasmuch as the voltage developed in some of the divider components is not subject to appreciable variation by reason of variations of the electron current flow between the associated multiplier electrodes, it is not necessary that the impedances of these divider components be of relatively small values. Such a condition is particularly true in the initial multiplier stages where the magnitude of the electron current flow is comparatively small.

It, therefore, has become the practice to employ a voltage divider consisting partly of a group of relatively low impedance components and partly of a group of relatively high impedance components. One such arrangement is disclosed in a copending application of Donald R. Rasley, Serial No. 512,541, filed December 2, 1943. The relatively high impedance divider components are used in association with those multiplier stages where the electron current densities are relatively small and the relatively low impedance divider components

2

are used in association with those multiplier stages where the electron current densities are relatively large. In this manner it is possible to provide accelerating voltages for the electron multiplier stages which are substantially constant, irrespective of fluctuations in the electron current densities representing intelligence signals and at the same time to minimize the consumption of power from the source of energy for the voltage divider.

10 Inasmuch as the energy source most conveniently used with apparatus of the character described consists of rectified alternating current energy, it becomes necessary to adapt such a power supply suitably to provide energy to a load consisting of both relatively high and low impedance elements. For certain television applications the source of alternating current energy from which the unidirectional power supply is derived also serves as the source of scanning 15 voltage for the deflector elements. Devices of this character used heretofore have been required to deliver unidirectional energy to only one load.

It, therefore, is an object of the present invention to provide a novel power supply for a load 20 circuit consisting of a plurality of impedance elements.

25 In accordance with this invention, there are provided a source of impulses and a load circuit including the series connection of a plurality of impedance devices. Additionally, there is provided a voltage multiplier of which the high voltage terminals are connected to the terminals of the load circuit. An intermediate terminal of the voltage multiplier is coupled both to the source 30 of impulses and to the junction point between two of the load circuit impedance devices. More specifically, the voltage multiplier may be that type of device known as a voltage doubler.

35 For a better understanding of the invention, together with other and further objects thereof, reference is had to the following description taken in connection with the accompanying drawing, and its scope will be pointed out in the appended 40 claims.

45 In the accompanying drawing:

Fig. 1 is a circuit diagram of apparatus embodying the present invention; and,

Fig. 2 is a group of curves illustrating the mode of operation of the apparatus of Fig. 1.

Having reference now particularly to Fig. 1 of the drawing, the source of impulses is a relaxation oscillator including a vacuum tube 11. The anode of this tube is connected through an inductive winding such as a coil 12 to the positive terminal of a source of direct current energy

such as a battery 13. The negative terminal of this battery is connected to ground. The cathode of the tube is connected through a resistor 14 to ground. The control grid 15 of the oscillator tube is connected through a coil 16 to ground. The coils 12 and 16 are inductively coupled in such polarity that the relationship is regenerative. The screen grid 17 of the oscillator tube is connected through a resistor 18 to the positive terminal of the battery 13.

The load circuit for the device comprises the series connection of a relatively high impedance device such as a resistor 19 and a relatively low impedance device such as a resistor 21. One terminal of the resistor 21 is connected to ground. The anode of oscillator tube 11 is coupled by an energy storage device such as a condenser 22 through a choke coil 23 to the junction point 24 between the load resistors 19 and 21. The resistor 21 is shunted by a condenser 25. The choke coil 23 and condenser 25 comprise a filter for a purpose subsequently to be described. A rectifier tube 26 is connected with its anode to the junction point of the condenser 22 and the choke coil 23. The cathode of the rectifier tube is connected to ground. A condenser 27 is connected between ground and the terminal 28 of the load resistor 19. A rectifier tube 29 is provided with its anode connected to the terminal 28 of the resistor 19 and with its cathode connected to the anode of the rectifier tube 26.

Referring now to the operation of the apparatus comprising the unidirectional power supply in accordance with this invention, a brief consideration will be given to the operation of the relaxation oscillator as a source of impulses. During conducting periods of the tube 11, when the current is increasing through the space discharge path of the tube and through the anode coil 12, the voltage induced in the control grid coil 16 impresses a voltage upon the control grid 15 suitable to maintain conduction in the tube. At the same time the anode voltage of the oscillator tube is maintained at a substantially constant value. When a critical interelectrode potential condition within the tube 11 is reached, the current increase through the tube and the coil 12 ceases and this current flow begins to decrease in magnitude. By reason of the fact that the current decrease through the coil 12 induces a voltage of opposite polarity in the coil 16, the control grid 15 is driven more negative than the space current cutoff value. Thus, the current decay in the coil 12 and the tube 11 is at a relatively rapid rate as compared with the rate of increase, and as a result the current flow soon is completely interrupted. The described cycle of operation then is repeated.

During periods of current decay in the coil 12 and in the tube 11 the voltage at the anode increases positively to a relatively high value. Since these periods are of relatively short durations there thus is developed at the anode of the oscillator tube a series of voltage impulses.

In considering the manner in which these impulses are utilized to develop two unidirectional voltages for impression upon load circuits of different impedance, assume that the condensers 22 and 27 are completely charged at the termination of one of the voltage impulses. During the time that the anode of the tube 11 is maintained at the described constant value the energy stored in the condenser 22 is slowly dissipated through the relatively low impedance of the resistor 21. Also, during this period the energy stored in the condenser 27 is dissipated also at a relatively

slow rate through the load resistors 19 and 21. The dissipation rates of the respective condensers are determined by the time constants of the dissipation circuits. These constants are a function of the values of each condenser and its associated load resistor. In the case of the dissipation circuit for the condenser 27 the resistor 21 has negligible effect upon the determination of the time constant for the reason that it is of a relatively low order of magnitude as compared with the resistor 19.

Immediately after the termination of one of the voltage impulses, the potential of the anodes of the rectifier tubes 26 and 29 are considerably negative with respect to their associated cathodes. These conditions are illustrated in Fig. 2, wherein the trace 31 represents the variation of the voltage at the point 24 of the load circuit and the trace 32 represents the variation of the voltage at the point 28 of the load circuit. These two voltages also correspond substantially to the respective voltages appearing at the anodes of the rectifier tubes 26 and 29. The dissipation of the energy stored in the condenser 22 during the periods between impulses is illustrated by the exponentially curved portion 33 of the trace 31. Similarly, the dissipation of the energy stored in the condenser 27 during these periods is illustrated by the exponentially curved portion 34 of the trace 32. It is seen that in both instances the negative voltages appearing at the load points 24 and 28 gradually are decreased. As a result of the development of these negative voltages, the respective anodes of the tubes 26 and 29 are maintained at negative potentials with respect to their associated cathodes. Neither of these tubes, therefore, is conditioned for conduction.

The impression of one of the positive impulses developed at the anode of the oscillator tube 11 upon the condenser 22 immediately changes the potential of the anode of the rectifier tube 26 from some negative value to ground potential. This change is illustrated by the rectangular impulsive portion 35 of the trace 31. The rectifier thus becomes conducting and energy derived from the impulse is stored in the condenser 22. During the impulse period no change is effected with respect to the rectifier tube 29. The condenser 27 continues to dissipate some of its stored energy through the load resistors 19 and 21.

Immediately upon the termination of the impulse, the voltage of the point 24 in the load circuit is abruptly changed to its most negative value represented by the point 36 on the trace 31. As soon as this voltage change is effected, the anode of the rectifier tube 26 immediately becomes more negative than the cathode of this tube and the tube ceases to conduct. Also, as an immediate consequence of the change of voltage at the load point 24 the cathode of the rectifier tube 29 becomes more negative than its associated anode. The tube 29 thus is conditioned for conduction to store energy in the condenser 27. The time required for this operation is extremely short. As a result, the voltage of the condenser and also that of the anode of the tube 29 and the point 28 of the load circuit is changed to the voltage of the load point 24 which at this time is at its most negative value illustrated by the point 36 on the trace 31.

For the purpose of illustrating the voltage changes during the charging period of the condenser 27, the trace 32 is displaced slightly in time from the trace 31. It is to be understood that the relationship between the traces 31 and

32 during the interval immediately succeeding the termination of one of the oscillator developed impulses is much exaggerated. The voltage change of the point 28 in the load circuit from the negative value represented by the point 31 on the trace 32 to its most negative value illustrated by the point 38 on this trace occurs substantially simultaneously with the depression of the voltage of the load point 24 to the negative value illustrated by the point 38 on the trace 31. The described cycle of operation is then repeated.

It is readily apparent from Fig. 2 that the average value of the load point 24 is maintained considerably negative with respect to ground. Also, it is evident that the average value of the voltage at the load point 28 is maintained at a negative polarity not only with respect to ground but also with respect to the average value of the negative potential at the point 24 of the load circuit.

The choke coil 23 with its associated filter condenser 25 prevents the feedback of energy from the load circuit to the oscillator circuit. In this manner the functioning of the relaxation oscillator is not affected by voltage changes occurring in the load circuit during the periods when the energy stored in the condensers 22 and 27 is being dissipated through the load resistors 19 and 21.

Instead of connecting the condenser 27 to ground, as shown, it may be connected alternatively to the junction point between the cathode and anode of the rectifier tubes 28 and 26, respectively. Also, it is considered to be within the scope of the instant invention to connect additional stages to the disclosed apparatus. Each one of such additional stages would be similar to that including the resistor 19, the condenser 27 and the rectifier tube 28. The connections required would be similar to those shown.

The values of the various circuit components instrumental in the development of the unidirectional power supply depend in some measure upon the voltage and load requirements of apparatus to be supplied with unidirectional voltages. Without intending to limit the present invention, the following table of values for the essential circuit components of a device in accordance with this invention is given by way of example. A source producing impulses at the rate of approximately 14,000 per second is used to supply energy at approximately 1500 volts with a current drain of approximately 0.8 milliamperes in a relatively high impedance resistor of 1,880,000 ohms and at approximately 1000 volts with a current drain of 7 milliamperes in a relatively low impedance resistor of 140,000 ohms.

Resistor 19	1,880,000 ohms
Resistor 21	140,000 ohms
Condensers 22 and 25	0.001 microfarad
Choke coil 23	0.5 henry
Rectifier tube 26	6x5 both sections in parallel
Condenser 27	0.008 microfarad
Rectifier tube 28	8016

While there has been described what, at present, is considered the preferred embodiment of the invention, it will be obvious to those skilled in the art that various changes and modifications may be made therein without departing from the invention, and therefore, it is aimed

in the appended claims to cover all such changes and modifications as fall within the true spirit and scope of the invention.

What is claimed is:

5. A unidirectional power supply comprising, a source of impulses, a load circuit including the series connection of a plurality of impedance devices, and a voltage multiplier having the high voltage terminals thereof connected to the terminals of said load circuit and an intermediate terminal thereof coupled to said source of impulses and to the junction point between two of said impedance devices.

10 15 2. A unidirectional power supply comprising, a source of impulses, a load circuit including a series connection of two impedance devices of different values, and a voltage doubler having the high voltage terminals thereof connected to the terminals of said load circuit and an intermediate terminal thereof coupled to said source of impulses and to the junction point between said load impedances.

20 25 3. A unidirectional power supply comprising, a source of impulses, a load circuit including the series connection of two impedance devices, a voltage doubler having the high voltage terminals thereof connected to the terminals of said load circuit and an intermediate terminal thereof coupled to said source of impulses, and means including a filter network for coupling the intermediate 30 terminal of said voltage doubler to one of said impedance devices.

35 4. A unidirectional power supply comprising, a source of impulses, a plurality of energy storage devices, one of said storage devices being connected to said impulse source, a plurality of energy dissipation circuits connected respectively to said energy storage devices, means operative under the control and for the duration of said impulses for effecting the storage of energy in said one storage device, and means operative in response to the inoperative conditioning of said first named means for effecting the storage of energy in another one of said storage devices.

45 50 5. A unidirectional power supply comprising, a source of impulses, first and second condensers, said first condenser being connected to said impulse source, two energy dissipation circuits connected in series and also connected respectively to said condensers, means operative under the control and for the duration of said impulses for effecting the storage of energy in said first condenser, and means operative in response to the inoperative conditioning of said first named means for effecting the storage of energy in said second condenser.

55 60 6. A unidirectional power supply comprising, a source of impulses, first and second condensers, said first condenser being connected to said impulse source, two energy dissipation circuits of different impedance values connected in series and also connected respectively to said condensers, means including a first rectifier operative under the control and for the duration of said impulses for effecting the storage of energy in said first condenser, and means including a second rectifier operative in response to the inoperative conditioning of said first rectifier for effecting the storage of energy in said second condenser.

65 70 7. A unidirectional power supply comprising, a source of impulses, a load circuit including the series connection of two impedance elements of different values, a first condenser connected between a terminal of one of said impedance elements and said impulse source, a second condenser connected to a terminal of the other of said im-

pedance elements, and two rectifiers connected respectively in parallel with said impedance elements.

8. A unidirectional power supply comprising, a relaxation oscillator having an output circuit for the development of a series of impulses, a load circuit including the series connection of a relatively high impedance element and a relatively low impedance element, a first condenser connected between one terminal of said relatively low impedance element and said output circuit, a second condenser connected to one terminal of said relatively high impedance element, a first rectifier connected in parallel with said relatively low impedance element, and a second rectifier connected in parallel with said relatively high impedance element.

9. A unidirectional power supply comprising, a relaxation oscillator having an output circuit for the development of a series of voltage impulses, a load circuit including the series connection of a relatively high impedance element and a relatively low impedance element, a first condenser

connected between one terminal of said relatively low impedance element and a relatively high voltage point of said output circuit, a second condenser connected to one terminal of said relatively high impedance element, a filter network connected between said first condenser and said relatively low impedance element, a first rectifier tube connected in substantial shunting relation to said relatively low impedance element between said first condenser and said filter network, and a second rectifier tube connected in parallel with said relatively high impedance element.
